DESIGN FOR A SHIRT COLLAR DISPLAY SUPPORT

Abraham Donner, St. Albans, N. Y.

Application October 6, 1938, Serial No. 80,287

Term of patent 3½ years

To all whom it may concern:

Be it known that I, Abraham Donner, a citizen of Germany, residing at St. Albans, in the county of Queens and State of New York, have invented a new, original, and ornamental Design for a Shirt Collar Display Support, of which the following is a specification, reference being had to the accompanying drawing, forming part thereof and in which:

I claim:

The ornamental design for a shirt collar display support, as shown.

ABRAHAM DONNER.
